CLAIM

The ornamental design for a faucet set, as shown and described.

DESCRIPTION

FIG. 1 is a front elevational view of a faucet set, showing my new design;

FIG. 2 is a left side elevational view thereof, the right side view being a mirror image of the left side shown;

FIG. 3 is a rear elevational view thereof;

FIG. 4 is a top plan view thereof;

FIG. 5 is a bottom plan view thereof; and

FIG. 6 is a left side elevational view of the spout thereof, the right side of the spout being a mirror image of the left side shown.
